UNITED STATES PATENT OFFICE.

PAUL AUGUST GOEDERT MONSELAER, OF WAIKAMIU, HONOLULU, TERRITORY OF HAWAII.

SUGAR-CANE MILL.

1,131,747.

Specification of Letters Patent. Patented Dec. 23, 1914.

Application filed January 21, 1911. Serial No. 813,432.

To all whom it may concern:

Be it known that I, Paul August Goedert Monselaer, a subject of the Queen of the Netherlands, residing at Waipahu, in the county of Honolulu and Territory of Hawaii, have invented certain new and useful Improvements in Sugar-Cane Mills; and I do hereby declare the following to be a full, clear, and exact description of the invention, such as will enable others skilled in the art to which it appertains to make and use the same.

This invention relates to sugar-cane mills, particularly to those mills having three rollers in the usual triangular arrangement; and its object is to increase the efficiency of such mills. It often happens in such mills, especially in twelve and fifteen roller mills, that the cane becomes crushed into particles so finely divided that it is difficult to make the last mills of the train take the feed. As a result, the capacity is reduced, the extraction of sucrose is reduced, and the moisture of the final bagasse is increased. The juice, which is extracted from the cane passed between the upper and the lower front or feed roller, is divided; part flows over the returner-bar and then down through the opening between the rear of the returner-bar and the discharge roller, while part is forced upward and forms a pool in the feed entrance space to the mill above the feed roller, in which the finely divided particles of cane are immersed when fed to the mill. The bagasse piles up in this pool and presses the underlying bagasse downward until it is carried between the rollers, the bagasse being lighter than the juice has a tendency to float. It is also found that the rollers oftentimes become smooth and refuse to feed. My invention provides means for permitting the escape of this juice. It contemplates providing a plurality of deep and narrow grooves arranged at intervals in the circumference of the lower front or feed roller, and means for keeping said grooves free from bagasse, cushion or cane, so that the juice may run in these grooves directly into the juice pan under the mill. In practice I have found that from twelve to fifteen circumferential grooves, each about $\frac{1}{2}$ " wide by $1\frac{1}{2}$ " deep, give good results with

$\frac{3}{2}$ " x $7\frac{1}{2}$ " rollers, but of course I do not confine myself to these dimensions.

By my improvements, the mill takes the 55 feed, as the juice escapes through the grooves, the capacity is greatly increased, a higher extraction of juice and a decrease in the moisture of the bagasse are obtained, and returner-bar troubles are largely eliminated.

In the accompanying drawings, forming a part of this specification, Figure 1 represents in sectional elevation a three roller sugar-cane mill embodying my improvements. Fig. 2 is a plan view of the feed roller. Fig. 3 represents on a larger scale a section of a portion of the feed roller showing the grooving.

Referring to the drawings, 4 represents the upper roller, 5 the feed roller and 6 the discharge roller respectively of a three roller sugar-cane mill. The feed roller 5 is provided along its length with a plurality of deep narrow grooves 5^a in its circumference, 75 and spaced preferably from four to six inches apart means are provided to prevent the grooves 5^a from becoming clogged with particles of bagasse. The toe of the returner-bar 7 could be so shaped as to fit the grooving of the feed roller 5, but it would prevent the passage of the juice in the grooves 5^a past the toe. I therefore provide the following: The channel 8 is bolted to the lugs 9 on the side caps 10, as most 85 mills are provided with such lugs for supporting a roll grooving lathe. A flat bar 11 is bolted to the channel 8 opposite each of the grooves 5^a in the feed roller 5. The end 11^a of each of the bars 11 is beveled and projects into one of the grooves 5^a, as shown in Fig. 1.

It will now be noted, that the juice extracted from the cane passed between the upper and feed rollers can escape in the grooves 5^a 95 directly into the juice pan 12, and that means are provided for keeping said grooves free from bagasse.

In the foregoing description the invention has been described as applied to the feed 100 roller, but it may, of course, also be applied to the discharge roller as well, if desired.

I claim:

1. A sugar cane mill having a plurality of

rollers; at least one of which is provided with deep and narrow circumferential grooving at intervals in its surface forming channels to conduct away the juice expressed from the cane.

2. A sugar cane mill having a plurality of rollers, at least one of which is provided with deep and narrow circumferential grooving at intervals in its surface forming channels to conduct away the juice expressed from the cane, and means to keep said grooves free of bagasse.

3. A sugar cane mill having three rollers in triangular arrangement, at least one of which rollers is provided with deep narrow circumferential grooving at intervals in its surface forming channels to conduct away the juice expressed from the cane.

4. A sugar cane mill having three rollers in triangular arrangement, at least one of which rollers is provided with deep narrow circumferential grooving at inter-

vals in its surface forming channels to conduct away the juice expressed from the cane, and bars engaging said grooves to free the latter of bagasse.

5. A sugar cane mill comprising a feed roller, a discharge roller, a top roller disposed in triangular arrangement, said feed roller being provided with deep and narrow circumferential grooving at intervals in its surface forming channels to conduct away the juice expressed from the cane.

6. A roller for sugar cane mills provided with deep and narrow circumferential grooving at intervals in its surface to serve as unobstructed channels to conduct away the juice expressed from the cane.

In testimony whereof I affix my signature, in presence of two witnesses.

PAUL AUGUST GODFRIED MESSCHAERT.
